[57] CLAIM

The ornamental design for a container for paint or the like, as shown and described.

DESCRIPTION

FIG. 1 is a left side elevation of a container for paint or the like showing my new design; the right side elevation being a mirror image thereof;

FIG. 2 is a fragmentary section of a bottom surface of the container thereof;

FIG. 3 is a top plan view thereof;

FIG. 4 is a front elevation thereof; and

FIG. 5 is a left side elevation thereof; with handle in raised position.

FIG. 1

FIG. 3
